UNITED STATES PATENT OFFICE

STEPHEN J. PALINKOS, OF NORWALK, CONNECTICUT

SWEATBAND

Application filed May 20, 1930. Serial No. 454,056.

This invention relates to hats and in particular to the sweatband portion thereof.

A particular object of the invention is to provide a sweat band for a hat in which the stitching used to hold the band in place is invisible.

A further object is to provide a sweatband, the lower edge of which will serve as a cushion to the head of the wearer.

10 A still further object is to provide a sweat band having no edge stitching which not only necessitates piercing the edge of the band which leaves a more or less rough edge all around the hat which is subject after 15 short wear to fraying, but also to prevent any piercing of the edge of the band whereby the sweat may find its way to the felt of the hat to eventually stain the same.

Another object is to so make a sweatband 20 that it may be readily creased at the proper place without presenting to the head of the wearer an uncomfortable feeling, and also to provide a sweatband which will not reduce the size of the hat materially, as is the 25 case in sweatbands where the full thickness of the sweatband leather or material is doubled.

Referring to the drawings wherein I have shown a preferred embodiment of the invention:

Figure 1 is a cross sectional elevation of a hat having applied thereto according to my improved method, a sweatband.

Fig. 2 is an enlarged section taken on the 35 line 2-2 of Fig. 1 and shows in detail just how the cushioning effect is obtained and also how the band is attached to the hat.

Fig. 3 is an edge view of the band showing the method of skiving the edge thereof 40 whereby its folded size is reduced and a cushion effect is obtained.

Fig. 4 is a view of a band made of thinner material than that shown in Fig. 3 and illustrates the method of skiving the same to 45 obtain the same results; and

Fig. 5 is an end view of the band illustrated in Fig. 4.

Referring to the drawings in detail, 5 indicates a hat, which may be of any well known type and comprises the usual brim 6

and crown 7, their meeting edge being indicated by 8. Adjacent this edge 8, I attach the sweat band 9 to the crown portion through the medium of suitable stitching 10 which is hidden on the outside of the hat by the outer band 11.

55 The particular method of producing the sweatband, as shown in Figs. 2 and 3 is to skive the same along one edge so as to reduce the thickness of the material for a distance back from the edge as at 12. This skiving produces a gradual thinning down of the material as at 13 so that when the skived portion 12 is turned back it will provide a hollow 14 which not only prevents directly 60 creasing the material which would eventually cause cracking, but it also provides a yieldable cushion which is comfortable to the wearer.

65 Arranged in the hollow 14 is rubber cement 16. This arrangement forms a guide 70 for the gauge attached to the sewing machine when the sweatband is being sewed into the hat. The cement also makes the sweatband more sweat-proof, as it is necessary for the perspiration to penetrate a 75 double thickness as is apparent.

80 This is an important feature and can be embodied in a band made up of a thinner material such as is illustrated in Figs. 4 and 5, by skiving only a groove 15 adjacent the edge of the band which will allow the band to be bent without cracking.

85 In sewing the band to the hat the skived portion only is sewn as at 10 to the hat and the remainder turned inwardly as illustrated. It will be also noted that the lower portion of the folded band extends beneath the lower edge of the crown of the hat and is bent to provide a flange 17 extending in the 90 direction of the brim of the hat as illustrated.

95 It will be apparent and particularly noticed that this sewing does not pierce the head engaging portion of the sweatband and therefore there is no chance of the sweat reaching the hat material through the needle holes, nor is there a rough surface presented to the head of the wearer.

100 The stitches being invisible give the hat

a more pleasing appearance and the method of skiving the leather, gives the cushion effect, does away with the tendency of the band to crack where it is bent, and does not detract from the size of the hat appreciably, 5 as originally manufactured.

Having thus described my invention what I claim as new is:—

In a hat and in combination, a hat crown portion, a brim extending from the edge of 10 said crown portion, a sweat band arranged within the hat crown portion adjacent to the joining of the brim thereto and including a portion spaced from the inner 15 side of the hat crown portion and a portion interposed between the first named portion and the wall of the crown portion and alone stitched to the latter, and a bight joining said portions and having opposite the inner 20 corner of the crown edge a comparatively thin portion whereby a cavity is formed between opposite portions of the sweat band, and rubber cement fully occupying said 25 cavity and joining the opposed portions of the sweat band and adapted to assist in preventing the passage of perspiration from the head of a wearer to the said corner of the crown.

In testimony whereof I affix my signature.

STEPHEN J. PALINKOS.
